UNITED STATES PATENT OFFICE

HENRIK HOYER, OF NEW YORK, N. Y., ASSIGNOR TO THE JACOBS BROS. CO., INC., OF BROOKLYN, NEW YORK, A CORPORATION OF NEW YORK

DESIGN FOR A SCALE

Application filed January 21, 1933. Serial No. 46,930. Term of patent 7 years.

To all whom it may concern.

Be it known that I, HENRIK HOYER, a citizen of the United States, residing at New York, in the county of New York and State of New York, have invented a new, original, and ornamental Design for a Scale, of which the following is a specification, reference being had to the accompanying drawing, forming a part thereof, wherein—

Fig. 1 is a side elevation, and Fig. 2 is a plan view of a scale, showing my new design.

I claim:

The ornamental design for a scale, as shown.

HENRIK HOYER.
